ABSTRACT

Heavy hydrocarbon oils are effectively desulfurized with minimum hydrogen consumption by being contacted with a hydrodesulfurization catalyst under desulfurization conditions including a temperature between 750°F. and 850°F. and a space velocity between 3 and 10 v/v/hr.

**HYDRO DESULFURIZATION OF HEAVY
PETROLEUM OIL AT HIGHER TEMPERATURES
AND SPACE VELOCITIES**

This invention relates to the desulfurization of petroleum fractions. More particularly, it is concerned with the catalytic hydrodesulfurization of heavy petroleum oils under conditions whereby the throughput and desulfurization of a unit are increased and the hydrogen consumption in the desulfurization procedure is reduced.

The catalytic desulfurization of petroleum hydrocarbons has been well known in the industry for many years. It has been discussed quite thoroughly in "Petroleum Processing" November 1956, pages 116-138. The literature discloses reaction conditions using fixed beds of catalysts in the broad ranges of temperatures of from 400°-900°F., pressures of from 50-5000 psig, hydrogen rates of from 200-20,000 standard cubic feet per barrel (scfb) and space velocities of 0.1-20 volumes of oil per volume of catalyst per hour (v/v/hr.)

Experience has shown that in the commercial desulfurization of heavy oils such as vacuum gas oils and heavier stocks, that is, oils having an initial boiling point of about 625°F. or higher, using fixed beds and conventional desulfurization catalysts, the start-of-run temperature using fresh or freshly regenerated catalyst will be between about 625° and 650°F. and the end-of-run temperature will be about 750°F., a gradual increase being made to compensate for loss of activity of the catalyst throughout the onstream period. Pressures range generally between about 500 and 1000 psig with hydrogen rates of about 500-2000 scfb. Ordinarily in conventional commercial units the space velocity is controlled to obtain the desired amount of desulfurization with 85-90% desulfurization being considered as the most practical from an efficiency standpoint.

It has been generally accepted in the industry that high temperatures result in shortened catalyst life due to loss of activity on the part of the catalyst through deposition of carbon and, in the case of residue-containing charge stocks, metal-containing compounds on the surface of the catalyst particles. It has also been generally accepted that hydrogen consumption is a function of the amount of desulfurization and that as the percentage desulfurization increases so does the amount of hydrogen consumed. It is also a general belief in the industry that, other things being equal, a decrease in space velocity is required to obtain an increase in desulfurization.

For ecological reasons, it has become necessary for refineries to treat more and more petroleum fractions to reduce the sulfur content thereof thus making desulfurization costs enormous, not only in the amount of equipment that must be built but also in the costs of processing the various petroleum fractions, not the least of which is the cost of hydrogen consumed. It has been ascertained that process improvements leading to a reduction in hydrogen consumption of 100 scfb of an increase in desulfurization from 90 to 95% or a reduction in pour point of 40°F. would result in a great economic improvement over current operations.

According to our invention, the efficiency of a hydrodesulfurization unit is improved by contacting a sulfur-containing petroleum oil having an initial boiling point of at least about 625°F. with a desulfurization catalyst at a temperature between 750° and 850°F., a pressure

between about 500 and 3000 psig and a space velocity between 3 and 10, preferably 4-8 v/v/hr. in the presence of added hydrogen in an amount between about 500 and 5000 scfb.

5 The feed used in the process of our invention is a heavy petroleum oil fraction having an initial boiling point of at least about 625°F. Non-limiting examples of such feeds are gas oils such as vacuum gas oils, atmospheric residua, vacuum residua, coker distillates, coal tar distillates and gas oils obtained from shale, tar sand and the like.

The hydrogen used in the process of our invention may be obtained from any suitable source such as reformer by-product hydrogen, hydrogen produced by 15 the partial oxidation of carbonaceous or hydrocarbonaceous materials followed by shift conversion and CO₂ removal or electrolytic hydrogen are satisfactory. The hydrogen should have a purity of at least 50% and preferably at least 65% by volume.

20 The catalyst used in the process of our invention generally comprises a Group VIII metal such as an iron group metal or compound thereof optionally composited with a Group VI metal or compound thereof on a refractory inorganic oxide support. Suitable Group VIII metals are particularly nickel and cobalt used in conjunction with tungsten or molybdenum. Preferably, the metals are in the form of the oxide or sulfide. Advantageously the iron group metal is present in an amount between about 1.5 and 10% by weight of the catalyst composite and the Group VI metal is present in an amount between about 5 and 30% also based by weight on the catalyst composite. Examples of refractory inorganic oxides which may be used as a support are silica, alumina, magnesia, zirconia and the like or mixtures thereof. In a preferred embodiment the support is composed for the most part of alumina with a minor amount, e.g. up to about 15 wt. % silica.

30 The catalyst is used as a fixed bed of particles which may be in the form of spheroids, pellets or cylindroids. 40 Advantageously, the catalyst particle's greatest dimension ranges between about 1/2 and 1/16 of an inch. Preferably, the catalyst particles are in the form of cylindroids having a maximum dimension of one-quarter inch. The reactant flow through the catalyst bed is concurrent and may be either up or down. In commercial installations the hydrogen and the oil usually are passed downwardly through the catalyst bed.

45 As mentioned above, the space velocity and temperature used in our process are considerably higher than those conventionally used in commercial installations.

50 The following examples are submitted for illustrative purposes only and should not be construed as limitations on the invention.

EXAMPLE I

A West Texas-New Mexico sour vacuum gas oil having a sulfur concentration of 1.85 wt. % (x-ray) is passed in upward flow through a fixed bed of cylindrical pellets of a catalyst comprising approximately 3 wt. % cobalt, 12 wt. % molybdenum, 83.0 wt. % alumina, 2-4 wt. % silica and having a surface area of 290 m²/g, a pore volume to 0.63 cc/g and an average pore diameter of 82.5A. Desulfurization is effected by passing hydrogen upwardly through the catalyst bed with the feed at a rate of 1500 scfb recycle hydrogen and 500 scfb fresh hydrogen at a pressure of 800 psig. The space velocities and temperature and other data appear below.

Run 1 represents typical commercial operation.

is approximately ten times as great as the catalyst deac-

TABLE I

Run No.	1	2	3	4	5
Temperature, °F.	670	670	750	800	850
Space velocity, v/v/hr.	1	4	4	4	4
Wt. % sulfur in product (x-ray)	0.22	0.63	0.18	0.06	0.05
% Desulfurization	88	66	90	97	97
Hydrogen consumption, scfb	450	213	350	310	340

It can be seen from the above data that not only can greater desulfurization be effected at a higher temperature and a higher space velocity than are used in conventional hydrogen desulfurization but it was also found that quite unexpectedly between 750° and 850°F. hydrogen consumption was lower than at other temperatures. This is not insignificant as a reduction in hydrogen consumption of 130 scfb during conventional operation means a saving of more than 1,000,000 cubic feet of hydrogen per day in a 10,000 barrel per day desulfurization unit, which by today's standards is of modest size. Many commercial desulfurization units have a capacity in excess of 20,000 barrels per day. In addition by making changes in the size of pumps, compressors, heaters and other auxiliary equipment the capacity of a conventional unit can be quadrupled. Either of these features represents a tremendous saving in the cost of desulfurizing a petroleum fraction at a time when the petroleum industry is being called on to desulfurize more and more petroleum fractions.

The results of Runs 1, 2, 3 and 4 show the effectiveness of the combination of high space velocity, high temperature and high linear velocity. In Run 1, the linear velocity is 116 whereas in Runs 2-5, it is 454. Run 1 shows good desulfurization but high hydrogen consumption. Run 2 shows low hydrogen consumption but a product containing more than 0.5 wt. % sulfur. Runs 3 and 4 with temperatures of 750° and 800°F., space velocities of 4 and high linear velocities show desulfurization to a level below 0.2 wt. %

EXAMPLE II

This example is a substantial repeat of Example I using the same charge stock and reactor, the significant difference being in the use of a space velocity of 8. Reaction conditions and other data are tabulated below:

TABLE 2

Pressure, psig	800
Temperature, °F.	800
Hydrogen rate, SCFB	2000
Product Sulfur, wt. % (x-ray)	0.18
% desulfurization	90.3
Hydrogen consumption, SCFB	260

The above run shows that a 90% reduction in sulfur can be obtained with a hydrogen consumption of only 260 SCFB. This is substantially the same amount of desulfurization obtained by conventional processing at a space velocity of 1 and a temperature of 670°F. However, here the hydrogen consumption is approximately 55% that of conventional processing and the throughput is 8 times as great.

It is also important that the pressure be at least 500 psig. Experimental data has shown that the rate of deactivation of the catalyst at a pressure below 500 psig

tivation rate at a pressure of about 800 psig when the reaction conditions encompass the high temperature and high space velocities of our invention.

EXAMPLE III

In this example, the same catalyst and charge stock used in the previous examples are used with the same reactor. Reaction conditions and other data are tabulated below.

TABLE 3

Run No.	7	8
Pressure, psig	400	800
Temperature, °F.	800	800
Space velocity, v/v/hr.	4	4
Recycle Hydrogen, SCFB	1500	1500
Fresh hydrogen, SCFB	400	500
Product sulfur, wt. %	0.22	0.06
% desulfurization	88.1	96.7
Hydrogen consumption, SCFB	220	310
Loss in activity, %	4.7	0.4
per barrel per pound of catalyst		

These data show 88% desulfurization with a hydrogen consumption of only 220 scfb. However, at 400 psig the catalyst deactivation rate is considerably greater than at 800 psig.

EXAMPLE IV

This example is similar to Example II but differs in that the charge is an Arabian vacuum gas oil having an API Gravity of 23.6° and a sulfur content (x-ray) of 2.2% and the catalyst contains 2.4 wt. % nickel and 7.8 wt. % molybdenum as the oxides supported on silica-stabilized alumina (2.5 wt. % silica based by weight on the catalyst composite). Reaction conditions and other data are tabulated below:

TABLE 4

Run	A	B
Pressure, psig	800	800
Temperature, °F.	825	800
Space velocity, v/v/hr	4	8
Hydrogen rate, scfb	2000	2000
Product sulfur, wt. %	0.18	0.28
% Desulfurization	91.8	87.2
Hydrogen consumption, scfb	315	290

These data show that a nickel-molybdenum catalyst is substantially equivalent to a cobalt-molybdenum catalyst.

Various modifications and variations of the invention as hereinbefore set forth may be made without departing from the spirit and scope thereof, and therefore, only such limitations should be imposed as are indicated in the appended claims.

We claim:

1. A method for effecting at least about 90% desulfurization of a petroleum oil having an initial boiling point of at least about 625°F. with a hydrogen consumption of between 220 and 350 scfb which com-

prises contacting said oil in the presence of added hydrogen with a catalyst comprising an iron group metal, oxide or sulfide thereof and a Group VI-B metal, oxide or sulfide thereof on alumina containing 2-15 wt. % silica at a temperature between 750° and 850°F. a pressure between about 500 and 800 psig and a space velocity between about 3-10 v/v/hr. and recovering from the desulfurization zone effluent a petroleum oil of reduced sulfur content.

2. The process of claim 1 in which the petroleum oil 10 is a vacuum gas oil.

3. The process of claim 1 in which the catalyst comprises cobalt and molybdenum.

4. The process of claim 1 in which the catalyst comprises nickel and molybdenum.

5. The process of claim 1 in which the catalyst comprises nickel and tungsten.

6. The process of claim 1 in which the space velocity is between 4 and 8 v/v/hr. and the hydrogen consumption is between about 260 and 350 scfb.
